FIG. 1.

FIG. 3.

INVENTOR.
JOSEPH LEDWINKA

BY *John P. Jacoby*
ATTORNEY.

UNITED STATES PATENT OFFICE.

JOSEPH LEDWINKA, OF PHILADELPHIA, PENNSYLVANIA, ASSIGNOR TO EDWARD G. BUDD MFG. COMPANY, OF PHILADELPHIA, PENNSYLVANIA, A CORPORATION OF PENNSYLVANIA.

DESIGN FOR A REAR AUTOMOBILE FENDER.

Application filed October 15, 1927. Serial No. 23,762. Term of patent 14 years.

To all whom it may concern:

Be it known that JOSEPH LEDWINKA, a citizen of the United States, residing at Philadelphia, in the county of Philadelphia, and State of Pennsylvania, has invented a new, original, and ornamental Design for a Rear Automobile Fender, of which the following is a specification, reference being had to the accompanying drawings, forming part thereof, wherein—

Fig. 1 is a side elevation and Fig. 2 is a perspective view as seen from the rear and side, of a rear automobile fender embodying my new design.

Fig. 3 is a sectional view taken substantially on the line 3—3 of Fig. 1.

Fig. 4 is a sectional view taken substantially on the line 4—4 of Fig. 2.

Figure 5 is a front elevation of my improved fender when viewed in the direction indicated by the lines 5—5 of Figure 1.

I claim:

The ornamental design for rear automobile fenders as shown.

In testimony whereof he hereunto affixes his signature.

JOSEPH LEDWINKA.
